INTERNAL COMBUSTION ENGINE

Filed July 12, 1930

Inventor:
Ferdinand Ebann

Attys.

UNITED STATES PATENT OFFICE

FERDINAND EBANN, OF EVANSTON, ILLINOIS

INTERNAL COMBUSTION ENGINE

Application filed July 12, 1930. Serial No. 467,408.

This invention relates to internal combustion engines of the multiple cylinder type, and is more particularly directed to the construction of the piston assembly comprising the pistons and a cross-head guide which are adapted to be utilized in the type of engine illustrated and described in my copending application filed March 20, 1929, and bearing Serial No. 348,400. The type of engine illustrated in my copending application and also illustrated in the present application is of a construction wherein the usual connecting rods or pitmen are eliminated and greater compactness is obtained, so that the bulk of the engine, as well as its weight, is materially reduced, thereby realizing certain important advantages among which may be mentioned greater simplicity, lower cost, and cheaper adjustments and repairs.

One of the objects of the present invention is to construct the reciprocating members comprising the pistons and cross-head member in such a manner as to reduce the cost of production thereof. The pistons and the cross-head member constitute units that may be easily cast and likewise easily machined and finished, and which may also be readily assembled in a short space of time.

Another object of the present invention is to construct the pistons and the cross-head guide as separate and independent units which may be fastened together by any suitable means permitting the removal of the pistons from the top of the cylinder block without necessitating the removal of any of the cross-head members from the position which they normally occupy with reference to the crank-shaft, and without necessitating the removal of the crank case. It is also to be noted that in engines of conventional present day construction the pistons can not be removed from either end of the cylinders without disturbing their respective connections with the crank-shaft, i. e., the crank-shaft bearings. In the engine of the instant application the crank-shaft bearings do not have to be touched to remove the pistons, thereby eliminating the refitting of those bearings on removal of any of the pistons. With this form of construction, it is seen that on removing

the cylinder head for renewing the gasket, re-grinding the valves, or for any other particular purpose, the pistons may likewise be easily removed and inspected, and new piston rings placed thereon, if necessary, or if the pistons are found to be in bad condition, they may be readily replaced by new pistons.

Other objects and advantages will be hereinafter set forth in the detailed description, reference being had to the accompanying drawings in which:

Figure 1 is a vertical cross section showing two of the cylinders and their pistons (one of the pistons being partly in section), the crank shaft, the connections between it and the pistons, and the crank case and water-jacket with the usual accompanying parts; and

Figure 2 is a plan view of the cross-head guide illustrating the threaded lugs which are adapted to receive the internally threaded pistons, and the boss that receives the fastening means for locking the pistons and cross-head guide against relative movement.

In the drawings I have illustrated my invention as embodied in a four-cycle engine comprising any desired number of cylinders arranged side by side in pairs, but it will suffice to describe the mounting and connections of a single pair of cylinders, as such description will apply to the other pairs of whatever number of cylinders may be provided to make up the engine as a whole. A single crank-shaft is used and in the case of an 8-cylinder engine it would be provided with four cranks arranged in the angular relation to each other commonly employed in 8-cylinder engines of the V-type wherein the two pistons lying in the same transverse vertical plane are connected to the same crank. The several cylinders may be cast in one or more blocks, as preferred, and they are surrounded by the usual water-jackets and equipped with intake and exhaust valves operated from cam-shafts in any suitable way.

Proceeding now to a description of my invention, 3 and 4 indicate, respectively, the two cylinders of a pair that are arranged side by side having a common partition 5 therebetween, provided with a water space 6 that forms a part of the circulating system.

Each of the cylinders is provided with a depending skirt 7, 8, respectively, which skirts are arcuate in cross-section and extend to a considerable distance below the cylinders proper. As clearly shown in Figure 1, the skirts 7, 8, are at the outer sides of their respective cylinders and serve as guides for a purpose that will be presently explained. A water-jacket 9 surrounds the upper portions of the cylinders and forms a part of the engine housing which is adapted to support a cylinder head 10 having suitable water passages therein and provided at its underside with firing chambers 11, 12 into which extend spark plugs 13, 14 as usual. Intake passages 15, 16 communicate, respectively, with the chambers 11, 12 and are normally closed by valves 17, 18. These valves are controlled by cams 19, 20 mounted on cam shafts 21, 22, respectively, and are arranged to actuate the lower ends of the valve lifters 25, 26 on which the lower ends of the valve stems are seated. It should be understood that these valve operating devices are shown and described merely as one preferred means for actuating the valves, but that, so far as my invention is concerned, any other suitable valve operating mechanism, or valve arrangement, may be employed.

The chambers 11, 12 overlie the ports in which the valves 17, 18 are seated, and also the outer portions of the cylinders, so that the fuel entering said chambers on the intake stroke of their respective pistons will be drawn thereinto in the usual way. Each cylinder is also provided with a valve controlled exhaust port (not shown), which may be of any approved type, so that the operation of the engine will be of the usual four-cycle principle, although the invention might be embodied in a two cycle engine, or one of the Diesel type.

The cylinders 3 and 4 are mounted on a crank case 27 at the bottom of which is a removable plate or oil pan 28 secured by screws 29. At the top of said crank-case is an inwardly projecting annular flange 30 on which the cylinder block rests, and on which it is supported by a marginal flange 31 located preferably adjacent to the upper ends of the skirts 7 and 8, the latter projecting down through the openings in the flange 30, as shown in Figure 1. Operating in the cylinders 3 and 4, respectively, are the pistons 32 and 33, provided with the usual piston rings. The pistons 32 and 33 are connected to and joined by a plate 35, the latter comprising the upper member of the cross-head guide 34. The piston skirts are internally threaded as at 36, and are adapted to be screwed on to the segmentary threaded legs 37 carried by the plate 35. This operation may be performed by any suitable tool, such as a spanner wrench, that can be inserted into openings 38 provided for that purpose at the top of each piston. Each piston is locked against turning by the use of a suitable bolt 39, the head of which is disposed within a recess formed in the head end of the piston, and the threaded end of which bolt engages an internally threaded boss 41, also carried by the plate 35. The bolt is provided with a tapered shank portion 42 adjacent the head thereof, being adapted to tightly seat itself into a tapered recess 43 in the piston, the purpose of which is to provide a seal to prevent escape of fuel mixture and exhaust gases into the crank case, as well as to maintain the proper compression.

The cross-head guide 34 comprises the upper plate 35, hereinbefore referred to, and a lower plate 44 which is bolted to the depending legs 45 extending from plate 35. It is between these two plates, 35 and 44 respectively, that the cross-head or slide-block 46 operates, as will be hereinafter explained. Each of the plates 35 and 44 can be easily manufactured, and although the plate 35 has been described as having separate externally threaded fragmentary lugs, and internally threaded bosses, it is obvious that the plate could be constructed with only two projecting bosses externally threaded to receive the respective pistons, with each boss provided with a tapped hole for receiving the ends of the bolts 39.

Mounted in suitable bearings 47 in the crank-case is a crank-shaft 48 having the requisite number of cranks, one of which is shown in section at 49. This crank portion lies between the transverse plates 35 and 44, and carries the cross-head or slide block 46 composed of upper and lower members 51 and 52, connected together by screws 53. The crank portion has bearing engagement in said cross-head, and the cross-head itself is arranged to slide transversely between the plates 35 and 44 against which its lower and upper surfaces bear. Lubrication of these parts may be arranged in any suitable way, as by the common splash system or pressure feed system.

It will be evident that as the crank-shaft 48 rotates, the cross-head 46 will reciprocate transversely between the plates 35 and 44, and at the same time the crank portion 49 will rotate about the axis of the crank-shaft 48. Rotation of the crank-shaft is effected by the action of the pistons 32 and 33, together with the other pistons comprising the engine as a whole.

By connecting the pistons in pairs directly with the cranks of the crank-shaft, the usual pitmen or connecting rods are eliminated, together with their connections, thereby greatly simplifying the construction. Also, by directly connecting the pistons with the crank, the engine is made more compact, and a considerable reduction in weight is effected.

Furthermore, the parts are much more easily accessible for adjustments and repairs.

The uppersurface of the lowerplate 44 and the under surface of the upper plate 35 may be made concave, and the surfaces of the bearing block or cross-head comprising the members 51 and 52 which contact with the aforementioned plates correspondingly convex, which aids in keeping the cross-head to a true rectilinear movement and avoids wear between the ends of said cross-head and the adjacent parts of the crank. However, this construction may be varied in any number of ways to produce the same guiding action, such as providing plates 35 and 44 with cross ribs adapted for cooperation within grooves or the like in members 51 and 52 of the cross-head.

The depending skirts 7 and 8 of the cylinders cooperate with the pistons 32 and 33 as well as with the cross-head guide member 34 to guide said pistons and said cross-head member, especially during the latter part of their downward movement, and avoid cramping, so that the pistons operate smoothly throughout the entire range of their movement. The engine may be assembled in the following manner: The cross-head guide member 35 is first inserted with its depending legs 45 adjacent the depending skirts 7 and 8 of the cylinders. The pistons, as a matter of choice, may be attached to member 35 and inserted upwardly into their respective cylinders on insertion of the plate 35 between the depending cylinder skirts, or, the pistons may be secured to the plate 35 after the balance of the engine comprising the crank and its cross-head members and the plate 44 have been assembled. When the plate 35 is in place, the crank-shaft, with the cross-head members fitted to the respective cranks of the shaft, is entered into the bearings 47 and the bearing caps fastened in place. It is to be noted that although the cross-head shown has the screws 53 with their respective heads adjacent the plate 35, it is obvious that the cross head may also occupy a position revolved at 180° to the position shown, in which case the heads of the screws 53 would occupy a position adjacent the plate 44. It is also apparent that the cross-head 46 may be so constructed as to be substantially square in form with all four sides thereof having convex surfaces, so that in the event that the two sides operating between the cross-head guide members should become worn and scored, it is possible to turn the cross-head member 90° to allow the other two sides of the cross-head member to engage the cross-head guide members 35 and 44.

When the crank-shaft is in place, plate member 44 comprising the lower way of the cross-head guide member, is secured in place by means of bolts. In order to take up wear between the plate members 35 and 44 it is

only necessary to remove the oil pan to allow access to the plate member 44, which may also be removed and some of the shims 55 taken out to compensate for the wear. During this same adjustment it is an easy matter to take up the wear of the cross-head block 46 by removing some of the shims 56 therefrom.

With this construction of internal combustion engine it is likewise possible to assemble all of the moving elements comprising the pistons, cross-head guide, cross-head and crank-shaft on the work bench. This is of great advantage in that it affords a simple and accurate method of fitting and checking the bearings of the parts having relative movement, and also facilitates the use of proper jigs for gauging and aligning all of the parts, especially the pistons and cranks. After assembling the operating mechanism comprising the pistons, cross-head, cross-head guide, and crank-shaft, as a unit on the work bench, it is possible to insert this unit assembly as a whole into the cylinder block from below, leaving only the crank-shaft bearing caps to be fastened into place.

Although I have confined my description to the particular disclosure illustrated in the drawings, it is obvious that many changes are possible which will not depart from the metes and bounds of this invention, and therefore, I do not wish to be limited to this exemplary embodiment but only insofar as is set forth in the appended claims.

What I claim is:

1. An internal combustion engine comprising a pair of parallel cylinders, pistons adapted to reciprocate in unison therein, each of said pistons having a conical recess formed in the head portion thereof, a crank shaft, a transverse guide operatively connected with said shaft, said pistons having threaded connections with said guide to facilitate removal of the pistons therefrom and from said engine, and locking means comprising bolts carried by the respective pistons and connecting with the transverse guide to secure the pistons against accidentally loosening from the transverse guide, said bolts being provided with a tapered shank portion having connection with said pistons within the conical recesses formed therein to establish a seal to prevent escape of fuel mixture and exhaust gases from within the cylinders.

2. An internal combustion engine comprising a pair of parallel cylinders, pistons adapted to reciprocate in unison therein, said pistons having threaded skirts, a crank shaft, and means directly connecting said pistons with said crank shaft to rotate the shaft by the reciprocation of the pistons, said means having threaded lugs cooperating with the threaded piston skirts for detachably securing the pistons to said means.

3. An internal combustion engine comprising

ing a pair of parallel cylinders, pistons adapted to reciprocate in unison therein, said pistons having threaded skirts, a crank shaft, means directly connecting said pistons with said crank shaft to rotate the shaft by the reciprocation of the pistons, said means having threaded lugs cooperating with the threaded piston skirts for detachably securing the pistons to said means, and locking means carried by each of the respective pistons engaging the aforesaid means for preventing accidental loosening of the pistons from said means.

4. An internal combustion engine comprising a pair of adjacent cylinders, pistons provided with threaded skirts operating in the cylinders, a cross-head guide comprising an upper plate having depending legs, threaded lugs on said upper plate, and a lower plate secured to said depending legs, said pistons being detachably connected directly to said upper plate by means of the threaded skirts engaging the threaded lugs thereon, a crank shaft, and a cross-head associated with said shaft and operating between the plates of said cross-head guide whereby the shaft is rotated by the reciprocation of the pistons.

5. An internal combustion engine comprising a pair of adjacent cylinders, pistons provided with threaded skirts operating in the cylinders, a cross-head guide comprising an upper plate having depending legs, threaded lugs on said upper plate, and a lower plate secured to said depending legs, said pistons being detachably connected directly to said upper plate by means of the threaded skirts engaging the threaded lugs thereon, locking means carried by the respective pistons connecting with said upper plate for preventing accidental detachment of the pistons from the plate, a crank shaft, and a cross-head associated with said shaft and operating between the plates of the cross-head guide whereby the shaft is rotated by the reciprocation of the pistons.

6. An internal combustion engine comprising a pair of adjacent cylinders, pistons provided with threaded skirts operating in the cylinders, a cross-head guide comprising an upper plate having depending legs, threaded lugs on said upper plate, and a lower plate secured to said depending legs, said pistons being detachably connected directly to said upper plate by means of the threaded skirts engaging the threaded lugs thereon, means comprising through bolts carried by the respective pistons connecting with said upper plate for preventing accidental detachment of the pistons from the plate, a crank shaft, and a cross-head associated with said shaft and operating between the plates of the cross-head guide whereby the shaft is rotated by the reciprocation of the pistons.

7. An internal combustion engine comprising a pair of adjacent cylinders, pistons op-

erating therein comprising head portions having conical recesses therein, and threaded skirts, a cross-head guide comprising an upper plate having depending legs, threaded lugs on said upper plate, and a lower plate secured to said legs, said pistons being detachably connected directly to said upper plate by means of the threaded skirts engaging the threaded lugs thereon, locking means cooperating between the pistons and the upper plate of the cross-head guide for preventing accidental detachment of the pistons from the plate comprising through bolts having tapered shank portions adjacent the heads thereof, said tapered shank portions engaging within the conical recesses formed in the piston heads to effect a seal for preventing fuel mixture and exhaust gases from escaping out of the cylinders, a crank shaft, and a cross-head associated with said shaft and operating between the plates of the cross-head guide whereby the shaft is rotated by the reciprocation of the pistons.

In witness whereof, I hereunto subscribe my name this 3rd day of July, 1930.

FERDINAND EBANN.
